EX

OR D 12,454

DESIGN FOR AN ORGAN-CASE.

Design No. 12,454, dated September 13, 1881.

UNITED STATES PATENT OFFICE.

EDWIN P. CARPENTER, OF WORCESTER, MASSACHUSETTS.

DESIGN FOR AN ORGAN-CASE.

SPECIFICATION forming part of Design No. 12,454, dated September 13, 1881.

Application filed July 30, 1881. Term of patent 7 years.

To all whom it may concern:

Be it known that I, EDWIN P. CARPENTER, of Worcester, in the county of Worcester and State of Massachusetts, have invented a certain 5 new and original Design for Organ-Cases; and I declare the following to be a description of my said design sufficiently full, clear, and exact to enable others skilled in the art to which it appertains to make and use the same, reference being had to the accompanying photographs, which form a part of this specification.

Figure 1 shows a perspective front and end view of my new design for organ-cases; and Figs. 2 and 3 show perspective views of the 15 back of the case, the latter with the swinging panel open.

In the lower front of the case there is a large central panel, *a*, above the pedals and extending about three-fifths of the width of front, or 20 namented with a raised pointed fret having incised line ornaments on its face. Said panel is flanked by small plain panels *b* at right and left, being separated therefrom by ornamental pilasters springing from brackets on the face of 25 the base-piece *c*, as shown. Above these panels projects the key-breast, the front piece, *d*, of which has a perforated serpentine and leaf ornament. At the right and left of the front are the end buttresses and brackets, *e e*, formed 30 and decorated in the style illustrated, their top ends receding above the breast with a double curve terminating at or nearly over the angle line of the case with ornamental stands *f*, for vases or lamps.

35 The ends of the case are finished with short lower panels, *g*, containing a carved central ornament and flanked by small molded buttresses, above which is arranged a plain incised or stenciled panel, *h*, surrounded by a plain 40 frame or border. A roll bead or ledge separates the upper and lower end panels. The breast-bracket, where it stands forward of the panel-frame, has a standing leaf ornament, the tips of the three leaves terminating in buttons 45 or rosettes, as indicated.

Upon the top of the case is a raised form composed of inclined ornamented pieces *i*, for supporting music-books. The inner ends of said pieces *i* are supported at some distance 50 apart by rows of small columns *i'*, surmounted by a miniature entablature and balustrade, while the outer ends rest upon the top of the

case ends and have ornamental guards or brackets, against which the books and music rest and are retained upon the shelves. The music-rack inclines back to rest against the end of the entablature of the columnar supports *i'*, as illustrated.

The back of the case is finished with two large central panels, *j k*, above the base-board 60 and moldings, the lower of said panels being ornamented, similar to the central front panel, *a*, with pointed ornaments, and the upper one made plain and decorated with a stenciled or gilded ornament. At the sides of these larger 65 panels are smaller panels, *l m*, the upper ones bearing carved ornaments and the lower ones plain. These several panels are separated from each other and the base by molded pilasters and transoms, as illustrated.

70 The large lower panels, *a* and *k*, may be hinged to open downward, or be made in two parts, to swing like doors.

What I claim, and desire to secure by Letters Patent, is—

75 1. The design for the top of an organ-case, consisting of the inclined shelves *i*, having their outer ends supported on the ends of the organ-case and their inner ends supported by the rows of columns *i'*, with entablature and balustrades, as shown.

2. The design for the front of an organ-case, consisting of the panels *a b*, pilasters, and buttresses, arranged and ornamented as shown.

3. The design for the back of an organ-case, 85 consisting of the panels *j k l m*, with pilasters, base and transoms, arranged and ornamented as shown.

4. The design for the end of an organ-case, consisting of the lower and upper panels, *g h*, 90 the breast-bracket *e*, and stands *f*, formed and ornamented as shown.

5. The organ-case built in the form shown, with the inclined open-centered top finish, and having its front, back, and ends finished and 95 decorated with ornamental panels and devices, arranged in the manner herein shown and described.

Witness my hand this 20th day of July, A. D. 1881.

EDWIN P. CARPENTER.
